UNITED STATES PATENT OFFICE.

MAX POEGE, JR., OF GLAUCHAU, GERMANY.

KNOTTING APPLIANCE.

1,099,128.

Specification of Letters Patent.

Patented June 2, 1914.

Application filed October 16, 1913. Serial No. 795,494.

To all whom it may concern:

Be it known that I, MAX POEGE, Jr., a citizen of the German Empire, residing at Glauchau, in Saxony, in Germany, have invented certain new and useful Improvements in Knotting Appliances, of which the following is a specification.

This invention relates to appliances for knotting or tying together threads, as for example in warp-tying machines, and its object is to provide an appliance of this kind combining the advantages of simplicity and reliable action.

The invention is illustrated in the accompanying drawing, in which—

Figure 1 is a front view of the apparatus, Figs. 2 and 3 being views of opposite sides thereof. Fig. 4 is a rear view, and Fig. 5 a plan view. Fig. 6 shows part of the mechanism, to a larger scale. Figs. 7 to 13 illustrate successive stages of the tying or knotting operation.

I will first describe the tying or knotting operation with reference, more particularly, to Figs. 7 to 13.

The loop is formed with the aid of a mandrel, designated 1, which is axially movable but not rotatable in a sleeve 2, into which it can be wholly retracted. A gripper 3 is rotatable about the position occupied by the forward end of the mandrel, when the latter is advanced, and the mandrel has at its front end a hook 4, movable in the direction of the axis of the mandrel and adapted 35 to grip the threads against the front surface of the mandrel. The two threads, which lie side by side, are represented in the drawing by the single line 5, and are fed to a fork 7, lying parallel with a pair of shears 6. The direction of the threads through 40 the fork toward the mandrel is inclined to the axis of the mandrel, as shown in Fig. 5. The inclined direction of the threads before the cutting enables the gripper 3 to clear 45 same during part of its rotation. The gripper 3, rotating in the direction indicated by the arrow in Fig. 7, grips the threads, which are then cut by the shears, the length cut off being carried around the advanced mandrel 50 by the gripper 3, as shown in Fig. 8. The mandrel is then partly retracted, to the position shown in Fig. 9, the loop being retained on the mandrel by a lateral projection 8. This partial retraction of the mandrel 55 brings the thread-ends held by the gripper 3 into proximity to the hook 4, which is

slightly advanced, whereupon the gripper 3 lays the threads behind the nose 4' of the hook, the latter being then retracted (Fig. 10) to grip the threads against the end of 60 the mandrel. The latter is then wholly retracted into the sleeve 2, so that the loop slides over its front edge (Fig. 11). In order to insure that the loop slides over the hook 4 the sleeve 2 has a projecting lip 10, 65 as shown in Fig. 6. The threads have in the meantime been released by the gripper 3, and are held solely by the hook 4. Thereupon a finger 9 arranged at one side of the sleeve 2 descends and engages the threads, 70 as shown in Fig. 12, pulling the loop over the thread-ends held by the hook 4 (Fig. 12) and in the course of its further descent drawing the loop tight to make a knot (Fig. 13), the thread being then drawn out from 75 behind the hook 4.

Figs. 1 to 6 show the mechanism for actuating the several parts described for effecting the knotting operation.

The mandrel 1 is connected to a spring 80 12, tending to retract it, and is guided by means of a cross-head 13 working in a slotted arm 14 fixed to the frame. The cross-head abuts against a cam 15 which has three flat-topped steps or ridges 23, 24, 25, and 85 16 is rotated by means of a crank-handle 16 for the purpose of advancing the mandrel.

The gripper 3 is carried by a sleeve 18 which is eccentric to the mandrel 1 and is rotatable on a bearing 17 through which the 90 mandrel passes. The sleeve 18 is rotated by means of elliptical gear wheels 19 and 20 and spur wheels 21, 22. During each revolution of the crank 16 the gripper 3 makes two revolutions. The eccentricity of the gripper 95 3 in relation to the mandrel 1 is for the purpose of securing an approach of the gripper toward the mandrel after the formation of the loop, so that at that stage there is only a short length of thread between the gripper 100 and mandrel. The elliptical gear is arranged so that the gripper movement is rapid during the formation of the loop, but then slows down while fresh threads are brought up.

While the thread is being gripped by the gripper 3 the cross-head 13 is on the crest of the largest ridge 23 of the cam 15, the mandrel being then wholly advanced (Fig. 7). In the course of the rotation of the cam 110 110 the cross-head slides first on to the ridge 24, allowing the mandrel to be retracted to the

position shown in Fig. 9, and then on to the ridge 25.

- 5 The shank 26 of the hook 4, working in a groove in the mandrel, is connected to a spring 27, tending to retract the hook. The shank is engaged with a sliding member 28, which works in a slot in the sleeve 2 and has a projection 29 outside the sleeve 2. An arm 30 fixed to the sleeve 18 carries an abutment 31. When the mandrel is wholly advanced the projection 29 is outside the path of the abutment 31, so that during the first and second revolutions of the sleeve 18 the abutment 31 clears the projection 29, but 15 when the mandrel has been retracted to the position shown in Fig. 9 the abutment 31 acts on the projection 29 and temporarily advances the hook 4, for the purpose already described.
- 20 The finger 9 is actuated by the spur-wheel 21; it is pivoted to a plate 33 and has a tail engaged with a link 34, which is guided by means of a stud 35 working in a slot 36 in the plate 33. The link 34 carries a pin 37.
- 25 During the preliminary stages of the knotting operation a spring 38 holds the finger 9 in the position shown in Fig. 7. Then a pin 32 on the wheel 21 wipes the pin 37 on the link 34, and the finger is depressed.
- 30 The shears 9 are actuated by a slotted cam 39 on the shaft of the wheel 21. A roller 41 mounted on one arm of a bell-crank 40 engages the slot of this cam. The other arm of the bell crank is forked and engaged with 35 the movable shear member 42. When the roller enters the part 44 of the cam slot the movable shear member is moved toward the other member, which is fixed, and the threads are cut.
- 40 What I claim as my invention and desire to secure by Letters Patent of the United States is:—

1. In a knotting appliance, the combination of a mandrel, means for gripping a 45 thread to the mandrel, a thread gripper arranged to revolve independently of and around said mandrel, means for operating said thread gripper whereby thread carried by said gripper is looped around the mandrel and delivered to said first mentioned means, and means for stripping said thread loop from the mandrel over said first mentioned gripping means.

2. In a knotting appliance, the combination of a mandrel, a hook axially slid able in 55 said mandrel, and adapted to hold a thread gripped between the same and the mandrel, a thread gripper arranged to revolve independently of and around the mandrel, means 60 for operating the revolving thread gripper, whereby thread carried by the gripper is looped around the mandrel and delivered to said hook, and means for stripping a thread loop from the mandrel over the hook.

65 3. In a knotting appliance, the combina-

tion of a mandrel, a thread gripper arranged to revolve independently of and about said mandrel, means for guiding thread past the mandrel to the gripper in a direction inclined to the axis to the mandrel, 70 means for operating the thread gripper whereby thread carried by the gripper is looped on the mandrel, and means for stripping a thread loop from the mandrel.

4. In a knotting appliance, the combination of a mandrel, a thread gripper arranged to revolve independently of and around said mandrel, means at one end of the mandrel for gripping a thread thereto, means for operating the revolving thread gripper, 80 whereby thread carried by the gripper is looped on the mandrel, means for axially moving the mandrel relative to the second mentioned gripping means, whereby said gripping means is positioned relative to the mandrel to engage a thread carried by the gripper at the end of the looping operation, and means for stripping a thread loop from the mandrel over said gripping means.

5. In a knotting appliance, the combination of a mandrel, a thread gripper arranged to revolve independently of and around the mandrel, means for operating the revolving thread gripper whereby a thread laid transversely of the mandrel is engaged by the gripper, looped around said mandrel and then released by the gripper, a second thread gripper carried by the mandrel at one end thereof for gripping a thread to the mandrel, said mandrel being movable axially relative to the second thread gripper, means for axially moving the mandrel whereby said second thread gripper is positioned relatively to the mandrel to engage a thread carried by the revolving thread gripper at the end of the looping operation, and a sleeve surrounding the mandrel whereby a thread loop formed on the mandrel is stripped from the mandrel over said second gripper in the course of axial movement of 100 the mandrel.

6. In a knotting appliance, the combination of a mandrel, a revolving thread gripper arranged to revolve independently of and around the mandrel, means for operating the revolving thread gripper whereby a thread laid transversely of the mandrel is engaged by the gripper, looped around the mandrel and then released by said gripper, a second thread gripper carried by the mandrel at one end thereof for gripping a thread to the mandrel, said mandrel being movable axially relative to said last mentioned gripper, means for axially moving said mandrel relative to said second gripper to position the said gripper relatively to the mandrel to engage a thread carried by the revolving gripper at the end of the looping operation, a lateral projection on the mandrel at one end thereof adapted to retain a 115 120 125 130

thread loop on the mandrel in the course of axial movement of the mandrel, and means for stripping a thread loop from said mandrel over said second gripper.

- 5 7. In a knotting appliance, the combination of a mandrel, a revolving thread gripper arranged to revolve independently of and around the mandrel, means for operating the revolving thread gripper whereby
10 a thread laid transversely of the mandrel is engaged by the gripper, looped around the mandrel and then released by said gripper, a second thread gripper carried by the mandrel at one end thereof for gripping a thread
15 to the mandrel, said mandrel being movable axially relative to said last mentioned gripper means for axially moving said mandrel relative to said second gripper to posi-

tion the said gripper relatively to the mandrel to engage a thread carried by the revolving gripper at the end of the looping operation, a sleeve surrounding the mandrel whereby a thread loop formed on the mandrel is stripped therefrom over said second gripper in the course of axial movement of the mandrel and a guide lip on said sleeve adapted to guide a thread loop on the mandrel over said second gripper.

In witness whereof I have signed this specification in the presence of two witnesses.

MAX POEGE, Jr.
